UNITED STATES PATENT OFFICE.

HENRY L. FERRIS, OF HARVARD, ILLINOIS.

TANK-HEATER.

No. 797,507.

Specification of Letters Patent.

Patented Aug. 15, 1905.

Application filed October 19, 1904. Serial No. 229,060.

To all whom it may concern:

Be it known that I, HENRY L. FERRIS, a citizen of the United States of America, residing at Harvard, in the county of McHenry and State of Illinois, have invented certain new and useful Improvements in Tank-Heaters, of which the following is a specification.

My invention relates to certain new and useful improvements in tank-heaters; and its object is to produce a device of this class which shall have certain advantages which will appear more fully and at large in the course of this specification.

To this end my invention consists in certain novel features, which are shown in the accompanying drawings as embodied in my preferred form of construction.

In the aforesaid drawings, Figure 1 is an elevation of my improved tank-heater. Fig. 2 is a central longitudinal section in the line 2 2 of Fig. 3. Fig. 3 is a top plan of the device. Fig. 4 is a horizontal section in the line 4 4 of Fig. 1. Fig. 5 is a horizontal section in the line 5 5 of Fig. 1. Fig. 6 is an under plan view with the base-plate removed, and Fig. 7 is a perspective view of the removable draft-partition and shaker.

Referring to the drawings, A is a base made in the form of a circular plate of metal with an upturned edge or flange a. Upon this base rests the body B of my improved device, the same being centered on the base by radially-projecting ribs b and secured to the base by screws b', passed through projecting ears b'' on the body of the heater and into the base. The base, it will be seen, can thus be removed at will. The body B, it will be seen, is cylindrical in form and provided with a laterally-extending annular portion B' and with a radially-projecting vertical flue B'', which terminates at and opens into the annular space B'. The space within the flue B'' is separated from the cylindrical portion of the heater by a removable partition B'', formed from a plate of sheet metal held in place between lugs b''.

In the lower part of the body B is an ash-pot C, provided with a handle by which it can be removed, and above this ash-pot is supported a fuel-basket D. This basket, it will be seen, has an outwardly-turned flange d, which rests upon lugs d', cast on the wall of the body B, so as to support the basket substantially on a level with the annular portion B'. The basket D is substantially cylindrical in form and perforated on the sides to form a grate. The bottom D' of the basket, which

is circular in form, rests upon a flange d'', extending inward from the side walls of the basket, and is rotatable thereon by means of a shaker E, extending along the outer side of the partition B'' and pivoted thereto. This shaker has a handle e at the upper end, which extends from the top of the heater. The lower end of the shaker extends inward under the edge of the partition B'', which is cut away for this purpose and is turned up at e' to engage with any one of the perforations in the bottom of the basket. When this shaker is rotated, it will be obvious that the bottom of the basket will be rotated and the matter within the fire-pot will be agitated to shake out the ashes.

F indicates the top of my improved heater, which is provided with a handle f, by which it can be lifted off to remove the basket and ash-pot. This cover is provided with a perforation f', which registers with the top of the flue and with a second perforation f'', operating as a check-vent. A damper F' is provided which will operate to close either or both of said perforations, as desired.

I realize that considerable variation is possible in the details of this construction without departing from the spirit of my invention, and I therefore do not intend to limit myself to the specific form herein shown and described.

I claim as new and desire to secure by Letters Patent—

1. In a device of the class described, the combination with the body of a tank-heater, of a base-plate upon which said body rests, ears upon the body, screws extending through said ears and into the base, an ash-pot within the bottom of the body, a fire-pot removably supported within the body above the ash-pot, an inlet-flue opening from the lower portion of the body adjacent to the fire-pot, a cover for the body and a suitable outlet-flue.

2. In a device of the class described, the combination with the body of a heater, having a radial projection forming an inlet-flue, of a removable partition cutting off the space within said projection from the body of the heater, a fire-pot within the heater, a rotatable bottom in the fire-pot, and a shaker pivoted to said removable partition and engaging with the rotatable bottom.

3. In a device of the class described, the combination with a cylindrical heater-body, of an ash-pot in the bottom thereof and a fire-pot of substantially the same internal diameter as

the body, said body having an annular swell at the level of the fire-pot and not extending below the same and an inlet-flue in communication with said annular swell.

4. In a device of the class described, the combination with the body of a tank-heater having radially-projecting ribs at its lower end, of a base-plate upon which the body rests having an upturned peripheral flange to engage said ribs to center the body, ears upon the body, screws extending through said ears and into the base, an ash-pot within the bottom of the body, a fire-pot removably supported

within the body above the body of the ash-pot, an inlet-flue opening from the lower portion of the body adjacent to the fire-pot, a cover for the body and a suitable outlet-flue.

In witness whereof I have signed the above application for Letters Patent, at Harvard, in the county of McHenry and State of Illinois, this 13th day of October, A. D. 1904.

HENRY L. FERRIS.
